(57) **CLAIM**

The ornamental design for a shoe midsole periphery, as shown and described.

DESCRIPTION

FIG. 1 is a perspective view of a shoe midsole periphery in accordance with my new design.

FIG. 2 is a left side view thereof;

FIG. 3 is a right side view thereof;

FIG. 4 is a top plan view thereof;

FIG. 5 is a bottom plan view thereof;

FIG. 6 is a rear elevation view thereof and

FIG. 7 is a front elevation view thereof.

FIG. 8 is a top plan view in cross section of the midsole of the shoe in FIG. 2 along line 8-8 in the direction of the appended arrows

FIG. 9 is a front elevation view in cross section of the midsole of the shoe in FIG. 2 along line 9-9 in the direction of the appended arrows

FIG. 10 is a front elevation view in cross section of the midsole of the shoe in FIG. 2 along line 10-10 in the direction of the appended arrows

FIG. 11 is a rear elevation view in cross section of the midsole of the shoe in FIG. 2 along line 11-11 in the direction of the appended arrows

FIG. 12 is a rear elevation view in cross section of the midsole of the shoe in FIG. 2 along line 12-12 in the direction of the appended arrows; and,

FIG. 13 is a rear elevation view in cross section of the midsole of the shoe in FIG. 2 along line 13-13 in the direction of the appended arrows.

The broken lines showing the remainder of the shoe represent unclaimed subject matter only and form no part of the claimed invention.

1 Claim, 8 Drawing Sheets
